SLUSHING SYSTEM

John L. Boyen, Orinda, Calif., assignor to Currier Company, a corporation of California

Application June 2, 1952, Serial No. 291,348

2 Claims. (Cl. 134—172)

My invention relates to degreaser equipment, and more particularly to a slushing system therefor.

The degreaser equipment to which the present invention relates, utilizes a highly volatile solvent such as trichlorethylene, which is vaporized and the items to be cleaned are immersed in the vapor which condenses thereon and dissolves the oil or grease from the item. Following such vapor treatment, it is the practice in many instances, to slush the item with liquid solvent to remove grit or dirt which was unaffected by the vapor treatment. Such slushing was conventionally accomplished by pumping the solvent with an impeller or other suitable type pump.

Trichlorethylene is quite difficult to retain in an enclosed space involving seams, in that it readily leaks through what might otherwise be deemed a watertight seam or joint. Consequently, in slushing systems utilizing pumps for driving the solvent through the slushing line, pump gaskets and other seals were not always a guarantee against leakage of the solvent.

Among the objects of the present invention are:

- (1) To provide a novel and improved slushing system for degreaser equipment;
- (2) To provide a novel and improved slushing system for degreaser equipment which eliminates the direct handling of a solvent by pumps;
- (3) To provide a novel and improved slushing system which shall be simple, effective and economical.

Additional objects of my invention will be brought out in the following description of a preferred embodiment of the same, taken in conjunction with the accompanying drawings wherein—

Figure 1 is a fragmentary side elevational view of apparatus including the improved slushing system of the present invention;

Figure 2 is a front elevational view of the slushing system of Figure 1.

Referring to the drawings for details of my invention in its preferred form, the degreaser equipment in which the same is embodied, comprises a tank 1 which is divided off by a vertical partition 3 to form on one side, a vapor chamber 5 in which liquid solvent is vaporized to produce a vapor region into which items to be cleaned are immersed.

On the other side of this partition, the tank section is divided by a horizontal partition 7 to form a solvent storage chamber 9 above, having a discharge pipe connection 11 to the vapor chamber, under control of a valve 13 connected in such pipe connection.

Surrounding the tank toward the upper end thereof, is a vapor condenser 15, which serves to condense the vapor at that elevation to preclude the same from escaping through the upper end of the tank, which normally remains open for the insertion and removal of such items as are to be cleaned. The condensate resulting from the operation of the condenser, is drained into the solvent storage chamber for reuse. The aforementioned equipment is basically old and not a part of the improvement constituting the subject of the present invention, except insofar as novel cooperation exists.

The improved slushing system, illustrated in conjunction with the previously described equipment, involves a slush tank 17 mounted on brackets beneath the horizontal partition. Such tank constitutes the source of liquid solvent for use in the slushing system, and receives its supply of solvent from the solvent storage chamber above,

2

by way of a pipe connection 21, from the lower end of the storage chamber to the slush tank. To provide for escape of air from said slush tank as the solvent flows into the same from the storage chamber, this slush tank is vented, and preferably to the solvent storage chamber, because such air will normally include some vapor, which should be retained in the system because of its high initial cost and its toxicity to human beings.

Accordingly, to permit of the venting of the slush tank into the solvent storage chamber, a pipe connection 23 is added which extends from the upper region of the slush tank to the upper portion of the solvent chamber. In this pipe connection, a three-way valve 25 is inserted, the connection utilizing two of the three controlled openings in such valve. The third and remaining controlled opening of the valve is connected to a source of compressed air (not shown) by a pipe connection 26. With the handle 27 of the valve in line with the vent connection, the air supply is blocked off, while with the handle 28 swung through a 90 degree angle to bring it in line with the air supply connection, the opening into the solvent storage chamber is closed off. Thus with the air supply line blocked, the pipe connection from the slush tank to the upper end of the solvent storage chamber will be open for venting purposes, while in its other position of adjustment, the valve will open the vent line for the flow of compressed air to the slush tank.

A slush line emerging from the lower region of the slush tank, extends upwardly as a pipe connection 29, to the upper end of the tank wall, where it is anchored, and continues within the tank as a flexible hose line 31 which terminates in a slushing wand 35.

In utilizing the above described slushing system for its intended purpose, the valve 27 is adjusted to the position 35 which cuts off the compressed air supply and exposes the opening in the upper end of the solvent storage chamber for venting of the slush tank. Under these conditions, solvent, in its liquid form, will flow from the lower end of the solvent storage chamber to the slush tank below, causing said tank to fill and the solvent to rise in the vent pipe connection until it reaches the level of solvent in the storage chamber. With the slushing wand in hand, ready for use, the valve is shifted over to close the vent opening in the storage chamber and at the same time open the system to the source of compressed air. Such compressed air will thus enter the slushing tank and drive the solvent therefrom through the slush line and wand. Reverse flow of solvent to the solvent storage chamber under the action of the compressed air, is blocked by a check valve 37 in the filling line 21.

Slushing is thus accomplished in the absence of any pump in direct contact with the solvent, and the problems connected with the use of a pump, as in conventional systems, are thereby avoided. The system, furthermore, is extremely simple and efficient.

Accordingly, while I have disclosed my invention in its preferred form, the same is subject to alteration and modification without departing from the underlying principles thereof, and while I have disclosed the same in considerable detail, I do not desire to be limited in my protection to such details, except as may be necessitated by the appended claims.

I claim:

1. A slushing system for degreaser equipment involving a vapor tank, said system comprising a solvent storage chamber, having a discharge opening, a slush tank, a fill connection from said storage chamber to said slush tank, a check valve in said connection, means for venting said slush tank, means for selectively forcing air under pressure through said vent means and into said slush tank, and a slush line extending from said slush tank, said slush line including a pipe section from said slush tank to the upper end of said vapor tank and a hose line leading from said pipe section and terminating in a slushing wand.

2. A slushing system for degreaser equipment involving a vapor tank, said system comprising a solvent storage chamber, having a discharge opening in the lower portion thereof, a slush tank disposed below the solvent level in said storage chamber, a fill connection from the lower

portion of said storage chamber to said slush tank, a check valve in said connection, a pipe connection from the upper portion of said slush tank to the upper portion of said storage chamber, a manually operable three-way valve in said last pipe connection having a third controlled opening for connection thereto of a compressed air line, and a slush line extending from the lower end of said slush tank, said slush line including a pipe section from said slush tank to the upper end of said vapor tank and a flexible hose line leading from said pipe section and terminating in a slushing wand. 10
